(57) **CLAIM**

The ornamental design for a hand-operated forklift, as shown and described.

DESCRIPTION

FIG. 1 is a perspective view of a hand-operated forklift showing our new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is an enlarged view of the encircled area 8 of FIG. 1;

FIG. 9 is an enlarged view of the encircled area 9 of FIG. 1;

FIG. 10 is an enlarged view of the demarcated area 10 of FIG. 4; and,

FIG. 11 is an enlarged view of the demarcated area 11 of FIG. 7.

The broken lines shown in the figures depict portions of the hand-operated forklift that do not form part of the claimed design. The dot-dash broken lines in the figures depict the boundaries of the enlargements and form no part of the claimed design.

1 Claim, 11 Drawing Sheets
